COVER ATTACHMENT FOR TELEPHONE HANDSETS

Walter Eric Youngberg, Cranston, R.I., assignor to Textron Inc., Providence, R.I.

Filed Jan. 15, 1968, Ser. No. 10,171

Term of patent 14 years

(Cl. D26—14)

The broken line representing the telephone handset is shown for illustrative purposes.

I claim:

The ornamental design for a cover attachment for telephone handsets, as shown and described.
